United States Patent Office

Des. 183,106
Patented June 24, 1958

183,106

BATHROOM SCALE

Joseph Palma, Jr., Wheaton, Ill., Courtney A. Leubner,
Milwaukee, Wis., and Robert L. Deschamps, La Grange
Highlands, Ill., assignors to The Brearley Company,
Rockford, Ill., a corporation of Illinois

Application August 26, 1957, Serial No. 47,513

Term of patent 14 years

(Cl. D52—10)

Fig. 1

Fig. 2

Fig. 1 is a top plan view of a bathroom scale, showing our new design;
Fig. 2 is a side view;
Fig. 3 is a front elevational view;
Fig. 4 is a rear elevational view, and
Fig. 5 is a perspective view.

We claim:

The ornamental design for a bathroom scale, substantially as shown.
